(34 Rue La France, Victoriaville, Quebec, Canada)

Filed Nov. 12, 1968, Ser. No. 14,379

Term of patent 14 years

Int. Cl. D12—14
U.S. Cl. D90—11

FIGURE 1 is a top perspective view of the steering device showing my new design;

FIGURE 2 is a top plan view thereof;

FIGURE 3 is an elevational view as seen from the front of FIGURE 1; and

FIGURE 4 is a cross-sectional view taken along line 4—4 of FIGURE 2.

The dominant features of my design reside in the portions shown in full lines.

I claim:

The ornamental design for a steering device for snowmobile, motorcycle or the like, as shown and described.
